UNITED STATES PATENT OFFICE.

ARTHUR C. BADGER, OF NEWTON, MASSACHUSETTS, ASSIGNOR TO BADGER FIRE EXTINGUISHER COMPANY, OF BOSTON, MASSACHUSETTS, A CORPORATION OF MASSACHUSETTS.

FIRE EXTINGUISHER.

Application filed May 10, 1924, Serial No. 712,262. Renewed November 12, 1928.

The present invention relates to fire extinguishers of the type in which, by inversion of the extinguisher, two reagents, previously kept separate from one another, are caused 5 to mingle and to generate gas whereby pressure is exerted to expel the liquid contents of the extinguisher. In such extinguishers the main body of the extinguishing liquid, containing in solution one of the complementary gas forming reagents, occupies the body of the extinguisher while the other reagent, in the liquid state or in solution, occupies an inner receptacle having a mouth normally closed by a stopper, which however 10 falls away from the mouth when the extinguisher is inverted.

The main object of the invention is to provide an extinguisher of the general type above indicated, in which the stopper is of a character adapted to spread and distribute the liquid flowing from the inner receptacle, when the apparatus is put to use, to the end that the reagent so distributed may mingle as completely and uniformly as possible with 20 the liquid outside of that receptacle, whereby maximum generation of gas may be obtained during the time required to discharge the extinguisher, but in such a controlled manner as to avoid too sudden generation of gas and 25 too violent application of pressure. Another result secured is the wide and general dissemination of gas bubbles through the mass of the extinguishing liquid, which is an important result in cases where the liquid contains 30 a substance capable of maintaining in a stable condition after its expulsion from the extinguisher, the foam produced by the disseminated gas. This object and result of the invention may therefore be more concisely stated as being to effect, by means of 35 the formation and arrangement of the stopper and its cooperation with the walls and outlet ports of the inner receptacle, a controlled generation of the maximum gas volume, and uniform distribution of the generated gas throughout the mass of the liquid in the form of small bubbles of not greatly varying dimensions.

Other objects of the invention are concerned with the structure of the inner receptacle, means for sealing the stopper when the extinguisher is in its upright position before use, means for guiding the stopper to insure its assumption of the desired position when 50 the extinguisher is used, and others, as will

appear from the following detailed description.

In the drawings which accompany this specification:

Figure 1 is a longitudinal sectional view 60 of the upper end of the fire extinguisher embodying the present invention, the same being in upright position prior to use;

Fig. 2 is a view of the same part of the extinguisher in its inverted position; 65

Fig. 3 is a perspective view in its inverted position of my improved stopper or cover for the inner receptacle;

Fig. 4 is a detail plan view of a suitable 70 guide for the stopper.

Like reference characters designate parts wherever they occur in all the figures.

The numeral 1 represents the outer shell of the extinguisher; 2 represents a ring forming the mouth of the extinguisher body and having a flange 3 to which the shell is secured in the usual, or any other suitable way, 4 represents a cap which is adapted to be screwed upon the ring 2, and may be of any form or construction, but preferably that commonly used with apparatus of this character. A gasket 5 is shown as representing packing means to make a leakage-tight joint between the cap and the mouth of the extinguisher. The main portion of the fire extinguishing 80 charge is placed in the outer shell or body of the extinguisher, and usually consists of water in which is dissolved one of the gas forming reagents, usually the alkaline reagent. If a substance or a composition of 85 substances is used to stabilize the foam caused by liberation of gas bubbles in the liquid, such substance or composition is preferably dissolved in the main body of the charge.

The complementary reagent, such as an acid, or an acid salt in liquid solution, is contained in an inner receptacle or bottle by which it is prevented from mingling with the other part of the charge prior to use. Such inner receptacle is here shown as a cylindrical jar or can 6, of a diameter small enough to pass through the mouth of the extinguisher body, and of a length great enough to contain the required amount of reagent. Any of the materials known to the art as being suitable for this use when in contact with the usual reagents may be employed for the receptacle of my present extinguisher. The upper end of the receptacle is preferably made by a tube or sleeve 7 to which the body part 6 of the re- 100 105 110

ceptacle is secured in any suitable way. The sleeve 7 is provided with an external shoulder 8 which is adapted to rest on lugs or a continuous ledge 9, inside of the mouth ring 2, whereby the inner receptacle is supported. The distance of the shoulder 8 from the extremity of said sleeve, is approximately equal to the distance of the lugs 9 from the end of the mouth ring, and its outer diameter approximately equal to the inner diameter of the ring, whereby the sleeve is clamped between the lugs and the cap, and is also withheld from lateral play. Ports 10 are formed in the sides of the sleeve 7 adjacent to the mouth ring 2, and on the inside of the sleeve below the ports is a ledge 11 provided for supporting the stopper. This ledge is preferably formed with an upwardly extending circular rib 12 between which and the wall of the sleeve is a trough 13 designed to hold some of the liquid of the outer charge so as to seal the stopper. The stopper 14 overlies the ledge 11 and is preferably formed with a complementary groove 15 to receive the upwardly directed rib 12, the latter being preferably beveled so as to make substantially line contact with the stopper. However, the main object of the invention does not depend on the sealing feature, and the latter may be omitted if desired. Then the seat for the stopper may be complementary to the curvature of the stopper, or flat; or indeed it may be made just as here shown, but the groove 15 in the stopper may be omitted.

From its outer circumference downward toward its axis, the stopper is curved with a concave curvature on all sides, this curvature being smooth and continuous except for the shallow and narrow groove 15 (provided there is such a groove). The lower extremity of the stopper is fashioned as a stem 16, the sides of which merge with the curve previously described, and the function of which is to guide the stopper, and prevent it from jamming in the sleeve 7, as it drops when the extinguisher is turned upside down. The stem passes through a guide 17 which is centrally supported in the receptacle by means of arms 18 suitably secured to the walls of the receptacle. A suitable construction of such guide and supporting arms is shown in Figure 4, where the structure is indicated as made of two metal straps overlapped at their inner ends and secured together, being bulged apart to provide the guideway between their points of attachment to one another, and their outer ends being bent over to form lugs 19 adapted to be secured to the walls of the receptacle. The guide may be otherwise made, however, for instance as a casting.

Preferably the curvature above described of the surface of the stopper beneath the widest part thereof is continued as a curve of revolution about the axis of the stopper, whereby all the elements of such surface in

planes radial to such axis are concave lines of smooth curvature. Such lines are tangent to the sides of the stem portion 16, such stem portion being approximately straight and cylindrical, and at such points of tangency the curvature of these longitudinal lines has the longest radius. From this point the radii of curvature of successive parts of the curve become progressively shorter, but even at the upper end of the curve, where it meets the rim of the stopper, the radius is so long that the center of curvature is outside of the rim of the stopper. In other words all the centers of curvature of all parts of the concave elements referred to are farther away from the axis of the stopper than the rim of the stopper. It results from this formation of the curve that when the extinguisher is inverted and the liquid pours out of the inner receptacle, the stopper spreads the liquid with a smooth and gradual change of direction and causes this liquid to be discharged directly at high velocity into the enveloping body of liquid in the outer part of the extinguisher. A particularly important fact is that the stopper when in the inverted position does not direct the flowing liquid upwardly or tend to cause a reversal in the direction of its flow, as would be the case if the center of curvature of the extremities of the surface elements before referred to were inside of the rim of the stopper and the under surface of this part of the stopper were formed with a groove or gutter. In general terms the characteristic curvature of the under side of the stopper is that which conforms to a stream flow, and is adapted to direct the flowing liquid outwardly without also directing it upwardly, and without causing sudden changes of direction or retarding the flow or making eddies.

In the discussion contained in the foregoing paragraph, the groove 15 has been disregarded. Although this groove may to a slight extent oppose the effects there described, yet its width and depth are so slight that its effect is negligible, and so may be disregarded in considering the characteristic formation and results of the under side of the stopper; but of course, if it is omitted as may possibly be done, it has no effect at all. This groove when provided, serves the purpose of causing the stopper to be firmly seated and centered, also sealed by the liquid, when the extinguisher is in its normal upright position.

In its other dimensions and proportions, the stopper is made to conform to the necessary distance between the cover 4 and the inner end of the mouth ring 2. When the extinguisher is inverted, the end of the stopper rests against the cover, and the length of this end from the rim of the spreading curve is such that the latter rim then lies in the same plane with, or possibly somewhat above, the inner end of the mouth ring 2, which is now uppermost. And the ports 10 have di-

mensions and positions appropriate to the position of the stopper, their upper edges being within, or so near to, the end of the mouth ring that they do not overlap the rim of the 5 stopper curve when inverted; and the height and width of these ports are great enough to permit a sufficient, but not too rapid flow of liquid from the inner receptacle.

What I claim and desire to secure by Letters Patent is:

1. A fire extinguisher of the invertible type, comprising an outer casing, an inner receptacle having a mouth far enough separated from the top of said casing to permit discharge of its contents when the extinguisher is inverted, and a stopper formed with a rim overlying said mouth and a central stem projecting into the receptacle and being centrally guided therein, the surface of the 15 stopper between its rim and stem being concave with a longitudinal curvature on lines conforming to the lines of stream flow.

2. A fire extinguisher comprising an outer shell, an inner receptacle having a stopper 25 seat, a discharge port between the seat and the top of the shell through which liquid may flow from the receptacle, when the extinguisher is inverted, into the space surrounding the receptacle, and a stopper within said 30 sleeve having a rim which overlaps and rests on said seat; said stopper having its under surface longitudinally curved from said rim on concave lines toward its axis.

3. A fire extinguisher comprising an outer shell, an inner receptacle having an interior 35 stopper seat, a discharge port between the seat and the top of the shell through which liquid may flow from the receptacle, when the extinguisher is inverted, into the space 40 surrounding the receptacle, and a stopper within said sleeve having a rim which over-

laps and rests on said seat and a stem extending through the seat; said stopper having its under surface curved from the rim to the stem on concave longitudinal lines which, 45 at the rim are approximately tangent to the plane of the rim and, as they approach the stem, become progressively more steeply inclined to said plane.

4. An invertible fire extinguisher comprising an outer casing having a mouth at one end, an inner receptacle depending from said mouth and having a stopper supporting ledge and lateral discharge ports between said ledge and the interior surface of the casing 55 at the mouth end thereof, a cap or cover for closing said mouth, and a stopper formed with a rim adapted to rest on said ledge to close the inner receptacle, and having an under surface with a concave curvature extending from its rim on opposite sides of its axis on longitudinal smoothly curved lines of increasing radii of curvature from the rim toward the axis; the stopper being free to fall from said ledge when the extinguisher 60 is inverted and having a length which causes it to be then arrested when the concave side of its rim is approximately flush with the surface of the outer casing surrounding the mouth opening.

5. A stopper for a fire extinguisher of the character set forth having a seating rim and a central projection extending from the plane of said rim, the surfaces of the stopper between said projection and rim being curved 75 with a concave curvature approximately tangent to the plane of the rim and having increasing radii of curvature from the rim toward the extremity of the projection.

In testimony whereof I have affixed my signature.

ARTHUR C. BADGER.
